UNITED STATES PATENT OFFICE.

EDWARD WESTON, OF NEWARK, NEW JERSEY.

DESIGN FOR A SUPPORTING-FRAME FOR ELECTRICAL INSTRUMENTS.

SPECIFICATION forming part of Design No. 23,157, dated March 27, 1894.

Application filed February 21, 1894. Serial No. 501,054. Term of patent 14 years.

To all whom it may concern:

Be it known that I, EDWARD WESTON, of Newark, Essex county, New Jersey, have invented and produced a new and original Design for Supporting-Frames for Electrical Measuring-Instruments, of which the following is a specification.

In the accompanying drawings Figure 1 is a front and Fig. 2 is a side view of a supporting frame showing my design.

The general outline of the design is rectangular, with openings A of parallelogram shape disposed parallel. The number of openings is not material; the width of the frame on the side B is greater than at the other sides C D E and than that of the bars F which

alternate with the openings A. The edges G of the side B appear raised. Depressions H appear at the sides C D E and bars F. From the side C and between the bars F extend 20 projections I. Also from the side B extend projections J. Also from side B extend a projection N having a circular aperture L and circular apertures M appear in the side C.

I claim—

The design for a supporting frame for an electrical measuring instrument substantially as herein shown and described.

EDWARD WESTON.
